UNITED STATES PATENT OFFICE.

WILLIAM F. BOSSERT, OF UTICA, NEW YORK.

SEMAPHORE BLADE.

Application filed June 29, 1921. Serial No. 481,229.

To all whom it may concern:

Be it known that I, WILLIAM F. BOSSERT, a citizen of the United States, and a resident of Utica, in the county of Oneida, in the State of New York, have invented new and useful Improvements in Semaphore Blades, of which the following, taken in connection with the accompanying drawings, is a full, clear, and exact description.

10 This invention relates to certain improvements in semaphores, and more specifically to a new and improved semaphore blade.

The main object of the invention is to provide a semaphore blade capable of use 15 and attachment to any usual spectacle, although there is considerable variance in the spaced distance of the bolt apertures in the spectacle for receiving the ordinary blade grips or clamps.

20 The spectacles in general use throughout the country have two different dimensions of drillings for bolt apertures. One dimension specifies $4\frac{1}{2}'' \times 4\frac{1}{2}''$ for the center of the bolt, while the other dimension demands $4'' \times 5''$, 25 and generally orders received for blades do not specify these particular dimensions. Therefore, considerable time is lost in securing the necessary information before orders can be filled. Further, due to this condition, many mistakes happen in shipping orders and the manufacturer is compelled to manufacture and keep a duplicate stock of blades on hand in order to fill orders reasonably promptly.

35 My invention avoids these uncertainties and duplications of blades by the provision of a blade which is capable of assemblage and use with spectacles having either dimension of bolt apertures.

40 A further object relates to the construction of a rigid, light and durable semaphore blade.

Other objects and advantages relate to the details of construction, form and arrangement of the blade, all as will more fully appear from the following description, taken in connection with the accompanying drawings, in which:

Figure 1 is a plan view of a spectacle having a blade of my invention assembled therewith.

Figure 2 is a plan view of a blade separate from the spectacle.

Figure 3 is an edge view of the blade of Figure 2.

Figure 4 is a fragmentary view of the end portion of the blade adapted to be secured to the spectacle.

Figure 5 is a section on line 5—5, Figure 60 4.

Figure 6 is a fragmentary view of the other end of the spectacle.

Figure 7 is a section on line 7—7, Figure 65 6.

The spectacle —1— is of the usual form and arrangement, and is provided with bolt apertures for cooperation with blade grips or clamps, which also extend through apertures in the blade —2—. In order to provide a blade capable of universal use in connection with spectacles having the various dimensions of bolt openings, as above described, the end of the blade adapted to be secured to the spectacle is provided with two pairs of slots, the pair —3— being near one edge of the blade while the pair —4— is near the opposite edge of the blade. Each pair of slots extends outwardly toward the edge of the blade, and the slots of each pair are inclined toward each other as they extend outwardly. The result of this construction is that the blade is capable of assemblage with and securement to spectacles which have their bolt openings at different spaced distances from each other. These 75 slots —3— and —4— are at exact angles to each other, as shown, the outer lateral extremities of the slots being adapted to one standard, as for instance $4'' \times 5''$, while the inner lateral extremities coincide with the 80 other standard, as $4\frac{1}{2}'' \times 4\frac{1}{2}''$.

85 The blade —2— is formed with a pair of corrugations extending throughout substantially the entire length of the blade. These corrugations begin at the end adapted to be secured to the spectacle, and are rounded in cross-section, as indicated, being of somewhat semi-circular form, and are positioned near the center of the blade, and between the pairs of slots —3— and —4—, and are 90 spaced apart by a flat portion —5— that is elevated slightly above the edge portions —6— in the completed construction, for the purpose of preventing marring or cracking of the enamel when the blade is secured to the spectacle.

100 The corrugations —7— and —8—, as stated, are formed near the middle of the blade at the end adapted to be secured to the spectacle, and extend in a substantially 105 110

parallel direction, and substantially parallel with the longitudinal axis of the blade throughout the said end portion of the same, which is adapted to lie in contact with the 5 spectacle. These corrugations then begins to diverge outwardly and incline away from each other, and toward the opposite edges of the blade, and then extend along the opposite edges of the blade to the opposite end 10 thereof.

As stated, these corrugations at the end adapted to be secured to the spectacle, are substantially of rounded form and are in cross section, and are of material height. 15 This height gradually diminishes and the corrugations flatten out from the point of diversion of the same to the opposite end of the semaphore blade, where the corrugations, as indicated, are somewhat flat at 20 their top portion.

The greatest stiffness of the blade is needed just beyond the point of contact of the blade with the spectacle, and for this reason the outward diversion of the corrugations along curved lines provides the required strength at this part of the blade. 25 The flattening decrease of the height of the corrugations as they extend from the end secured to the spectacle to the opposite end 30 of the blade provides ample stiffness where most needed against wind pressure, and at the same time substantially eliminates any possibility of snow or ice lodging at the outer portions of the blade where increased 35 or extra weight will have the most pronounced effect on the operation of the same.

The edges of the blade beyond the point of contact of the end portion of the blade with the spectacle are provided with flanges 40 —9— and —10— extending from the body of the blade in a direction opposite of the extension of the corrugations —6— and —7—, to further strengthen the blade and prevent the same from buckling.

45 It will be obvious that by this construction I have produced a blade that is capable of universal use with the different spectacles described, and that the same is also of an unusually, rigid and durable structure capable of being made of a single piece of 50 relatively thin sheet metal.

Although I have shown and described a specific construction and form of blade, as 55 illustrative of a perhaps preferred embodiment of my invention, I do not desire to limit myself to the details of construction or form of the same, as various changes and modifications may be made in each without departing from the invention as set forth 60 in the appended claims.

I claim:

1. A semaphore blade having at one end a plurality of pairs of slots, the slots of each pair being inclined outwardly toward 65 each other.

2. A semaphore blade having at one end two pairs of slots wholly within the body of the blade, the slots of each pair being inclined outwardly to each other.

3. A semaphore blade having at one end 70 a plurality of pairs of slots, the slots of each pair being inclined outwardly toward each other, and a pair of corrugations extending longitudinally throughout substantially the entire length of the blade. 75

4. A semaphore blade having at one end two pairs of slots wholly within the body of the blade, the slots of each pair being inclined outwardly to each other, and a pair of corrugations extending longitudinally 80 throughout substantially the entire length of the blade.

5. A semaphore blade having at one end a plurality of pairs of slots, the slots of each pair being inclined outwardly toward 85 each other, a pair of corrugations extending longitudinally throughout substantially the entire length of the blade, the edges of the blade being bent to form flanges extending in a direction opposite to the projection of 90 said corrugations.

6. A semaphore blade having at one end two pairs of slots wholly within the body of the blade, the slots of each pair being inclined outwardly to each other, and a pair 95 of corrugations extending longitudinally throughout substantially the entire length of the blade, the edges of the blade being bent to form flanges extending in a direction opposite to the projection of 100 said corrugations.

7. A semaphore blade having two corrugations extending throughout substantially its entire length, said corrugations beginning at one end and spaced from the opposite 105 edges of the blade, and extending parallel for a portion of the blade, and then diverging outwardly from each other to the opposite edges of the blade and extending along the opposite edges to the opposite end of 110 the blade.

8. A semaphore blade having two corrugations extending throughout substantially its entire length, said corrugations beginning at one end and spaced from the opposite edges 115 of the blade, and extending parallel for a portion of the blade, and then diverging outwardly from each other to the opposite edges of the blade and extending along the opposite edges to the opposite end of the blade, 120 and flanges projecting from the opposite edges of the blade in a direction opposite to the direction of projection of said corrugations.

9. A semaphore blade having two corrugations extending substantially throughout its entire length, said corrugations beginning at one end and spaced for a portion of their 125 length from the opposite edges of the blade, and diverging outwardly from each other 130

toward the opposite edges of the blade, and extending along the opposite edges to substantially the opposite end of the blade, and flanges extending laterally from the opposite 5 edges of the blade.

10. A semaphore blade having means permitting its securement to spectacles having bolt openings varying in spaced dimensions.

11. A semaphore blade having two corrugations extending substantially throughout its entire length, said corrugations beginning at one end and spaced for a portion 10 of their length from the opposite edges of the blade, and diverging outwardly from 15 each other toward the opposite edges of the

blade and extending along the opposite edges to substantially the opposite end of the blade, flanges extending laterally from the opposite edges of the blade, and bolt openings upon opposite sides of said corrugations 20 at the end of the blade, where said corrugations are spaced upon the opposite edges of the blade.

In witness whereof I have hereunto set my hand this 22d day of June 1921.

WILLIAM F. BOSSERT.
